S. WALKER,
INDICATING APPARATUS,
APPLICATION FILED NOV. 1, 1920.

1,374,788.

Patented Apr. 12, 1921.

UNITED STATES PATENT OFFICE.

STANLEY WALKER, OF KINGS LYNN, ENGLAND.

INDICATING APPARATUS.

1,374,788.

Specification of Letters Patent. Patented Apr. 12, 1921.

Application filed November 1, 1920. Serial No. 421,150.

To all whom it may concern:

Be it known that I, STANLEY WALKER, a subject of the King of Great Britain and Ireland, and residing at Alma Lodge, Ter-
5 rington St., Clement, Kings Lynn, in the county of Norfolk, England, have invented certain new and useful Improvements in and Relating to Indicating Apparatus, of which the following is a specification.

10 This invention relates to indicating apparatus more particularly for use in recording or indicating the date of examination, overhauling, or testing or the like of any kind of machinery, for example, aeroplanes, rail-
15 way stock or bridges, fire appliances, or any other plant that requires periodical attention, overhauling, oiling, &c.

The apparatus according to the invention comprises one or more plates, dials or the 20 like having the desired indicating marks thereon, and means for setting such plates or dials to indicate the desired record.

According to one form of the apparatus two plates or dials may be provided, one 25 dial having the numbers 1 to 31 arranged thereon while the other may have the numbers 1 to 12, whereby by suitably setting the dials a given date comprising the day and month may be recorded.

30 The dials or plates are preferably of circular shape mounted concentrically behind a face plate having openings thereon whereby the desired numbers may be read through said openings.

35 In order to set the dials a detachable key may be provided and the dials when in the set position are held in such position by suitable locking means.

Further features of the invention will be 40 hereafter described and defined in the claims.

The accompanying drawings illustrate the carrying out of the invention according to two forms by way of example.

45 Figures 1 and 2 are a front elevation and sectional plan of one form of apparatus suitable for indicating the date of oiling machinery;

Fig. 3 is a side view of an operating key for use therewith.

50 Fig. 3a is a plan view of said key.

Figs. 4 and 5 are front and sectional elevations of a second form for use as a calendar, while

55 Fig. 6 shows details of the clutching devices therefor.

In carrying the invention into effect ac-

cording to one form of apparatus, shown in Figs. 1 to 3, a pair of superposed disks or plates 7 and 8 are provided mounted to rotate about the same axis. The front disk 7 60 is smaller than the rear disk 8 whereby the indicating marks on the latter are exposed.

The larger disk 8 is provided with the numbers 1 to 31 thereon so as to indicate days while the smaller disk 7 which indicates 65 months is provided with the numbers 1 to 12. The rear disk 8 is provided with a central boss 9 having a squared recess 10 therein whereby it may be rotated by means of a 70 suitable key.

The smaller disk 7 is provided with a sleeve 11 whereby it is mounted upon the central boss 9 and in order to rotate it the outer end of the sleeve is provided with grooves or recesses 12 to accommodate a pin, 75 key or spanner.

The disks are mounted behind a face plate 13 made of sheet metal and such plate is dished or stamped out to provide recessed portions to accommodate the disks. A central recessed portion 14 is also provided having an aperture therein in which the sleeve 11 of the smaller disk 7 fits so as to form a bearing for said sleeve.

The disks are inclosed by a back plate 15 80 which is fastened to the face plate in any suitable way, as for instance, by screws. The back plate is provided with a central aperture in which a reduced part 16 of the boss 9 on the larger disk is adapted to fit to form 90 a bearing.

Apertures 17 are provided in the face plate 13 whereby the numbers on the disks are exposed to indicate the desired date. Such apertures may be covered with glass, 95 or other suitable material.

To complete the date the year is preferably painted on the face plate as indicated at 18 or impressed thereon in any other suitable way, or if desired a third disk may be 100 provided to indicate the year.

In order to hold the disks in the desired position the edges thereof are provided with recesses or teeth 19 into which a spring pawl 20 engages.

105 The teeth and pawl are preferably arranged so that rotation is only possible in one direction as indicated by the arrow.

The pawls may be mounted on the face plate, suitable recesses 21 being stamped out 110 to accommodate them.

Lugs 22 are provided preferably on the

face plate whereby the device may be fastened in any convenient position with regard to the machinery or plant to which the record relates.

- 5 Suitable words or marks such as "oiled," "painted," "repaired," "rebuilt" or the like may be impressed or otherwise mounted upon the device according to the use to which it is to be put.
- 10 A pivoted plate 23 is provided to cover the ends of the boss and sleeve when it is not desired to operate them by means of a key.

Fig. 3 shows a suitable spanner for use 15 with the above described apparatus. The spanner or key 24 is formed in the nature of a cranked member having at one end thereof a squared portion 25 to fit the squared recess in the boss 9, and having a 20 pin spanner 26 at the other end to engage the recesses 12 in the sleeve 11.

Referring now to Figs. 4 to 6 which show 25 an apparatus arranged as an ordinary calendar three disks 27, 28, 29 are provided to indicate respectively the day of the week, the day of the month and the month. The disks are provided with central sleeves 30, 31, 32, fitting within each other, the outer sleeve 30 being mounted to rotate within a bearing 33 30 in the cover 34.

The cover 34 is recessed to accommodate 35 the disks and is provided with openings or windows through which the indications on the disks may be read.

The edges of the disks are toothed and engage with spring pawls 35 whereby they are held in position and backward rotation is prevented.

In order to rotate the disks as desired, the 40 sleeves 30, 31, 32 are formed with inwardly projecting teeth 36, 37, 38 with which teeth 39 on a clutch or operating spindle 40 are adapted to engage.

Normally the teeth 39 are in engagement 45 with the teeth 37 on the middle sleeve 31 being held in such position by opposed springs 41, 42, bearing against an abutment plate 43, fixed to the back board 44 and also against a collar 45 and a screw head 46 on 50 the pin 40.

In order to engage the teeth 36 or 38 the pin 40 is pulled outwardly or pushed inwardly by means of the operating head 47 which is screwed to the pin or fixed in any 55 other suitable way.

Free spaces are provided between the teeth 36 and 37, 37 and 38, whereby the clutch teeth cannot operate two disks at the same time.

The marking for indicating the year may 60 be impressed on the cover in any suitable manner or a detachable plate may be provided which is let into a suitable recess in the cover and is fixed in position by screws.

Instead of using the device to indicate 65 a date, the disks may have any other suitable indicating marks thereon.

For instance, the device may be used to indicate the movements of a doctor, the inner disk indicating the hour, the middle disk 70 the minutes say to every five, while the outer disk would have such indications as "Today," "To-morrow," "This evening." The name of the doctor could be suitably impressed on the front cover at the top thereof 75 while immediately below a separate reversible device may be provided giving the indications "Out," "In at."

Having now described my invention what I claim as new and desire to secure by Letters Patent is:—

1. In a date reminder or indicator, a plurality of superposed indicating disks rotatable about a common axis, and clutch members carried by the disks and arranged at 85 the centers of the disks adapted to be engaged by clutch members on a key in order to rotate the disks to show the desired indication, said disks being provided with centrally disposed sleeves which carry the 90 clutch members, and the clutch members being spaced apart to permit operation of one disk by the key without operating an adjacent disk.

2. A date reminder comprising a plurality 95 of superposed indicating disks each provided at its center with a sleeve, the sleeves of said disks being concentric with one another and each sleeve being provided with clutch members, a stem rotatably mounted 100 in said sleeves and provided with lugs designed to engage said clutch members for turning the same, and a plurality of springs mounted on said stem for holding the stem in normal position out of engagement with 105 either of said clutch members.

In testimony whereof I have signed my name to this specification.

STANLEY WALKER.
